UNITED STATES PATENT OFFICE.

EDWARD C. CARRIS, OF WASHINGTON, IOWA, ASSIGNOR OF ONE-HALF
TO SETH D. CARRIS, OF DUBLIN, IOWA.

MATCH-BOX.

SPECIFICATION forming part of Letters Patent No. 761,625, dated May 31, 1904.

Application filed November 11, 1903. Serial No. 180,700. (No model.)

To all whom it may concern:

Be it known that I, EDWARD C. CARRIS, a citizen of the United States, and a resident of Washington, in the county of Washington and State of Iowa, have invented a new and Improved Match-Box, of which the following is a full, clear, and exact description.

This invention relates to match-boxes of a class that supply a single match at a time for removal from the box, and has for its object to provide novel details of construction for a device of the class indicated which adapt the improved match-box to mechanically elevate a single match from a number in the receptacle and retain it at a selected point on the box for removal, the mechanism being arrested by the elevated match and operating for the lifting of another match only when the one held is removed.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a perspective view of the improved match-box having a portion of one side wall removed to expose the interior parts. Fig. 2 is a transverse sectional view substantially on the line 2-2 in Fig. 3. Fig. 3 is a partly-sectional side view of the improved match-box, showing the mechanical details as they appear during the act of lifting matches from the holder-tray; and Fig. 4 is a view similar to Fig. 3, but showing detail features of the device in the slightly-altered position they assume on completion of the selection of a single match for subsequent elevation and removal.

The box-body may be formed of any suitable material and be shaped to give it an ornamental appearance. As shown, one form thereof may be rectangular, comprising an oblong structure open at the ends and having two sides 5, spaced apart in vertical parallel planes by the bottom wall 5^a and a top wall, the latter being formed in two sections 5^b 5^c,

that may be hinged together, as shown at a. 50 Between the sides 5 a cylinder 6 is introduced, which is formed of any preferred material, and at the centers of its parallel walls pivots b b are projected therefrom, which loosely engage opposite perforations in the sides 5, 55 whereby the cylinder is held to rotate, and, as shown, a portion of the cylinder 6 is projected up through an opening c in the section 5^b of the top of the box-body. The section 5^b of the top of the box-body is secured upon the 60 upper edges of the sides 5; but the section 5^c is not affixed thereto and serves as a lid. Below and near the lid 5^c a tray-board 7 is secured by its side edges between the sides 5, this board having a suitable inclination from 65 the like ends of the sides 5 toward and near to the lower portion of the cylinder 6, and at said downwardly-inclined end of the tray-board a transverse ledge or strip 7^a is secured, which 70 loosely contacts with the cylinder, as shown in Figs. 1, 3, and 4. Upon the cylinder 6 two lifting-fingers d are secured in a plane parallel with the axis of the cylinder and respectively positioned near an end wall of the cylinder, 75 said fingers, that may be pieces of wire-rod material, having an equal inclination toward the lid 5^c.

In the lower edge of the tray-board 7 and in the ledge 7^a two spaced notches e are formed, 80 through which the fingers d may freely pass, and they also have clearance from the transverse adjacent edge of the fixed top section 5^b.

In the space provided between one end wall of the cylinder 6 and a side wall 5 of the box-body a spur-gear 8 is mounted and secured 85 upon one of the pivots b, said gear meshing with a gear-wheel 9, which in turn meshes with another gear 10, mounted and fixed upon the shaft 11 of a spring-motor 12, designed by its geared connection therewith to communicate rotatable movement to the cylinder in the direction of the curved arrow x in Fig. 4.

A tripping-shaft 14 is held to rock transversely on the cylinder 6 by the staples g or other suitable means, and from said shaft two 95 arms h are projected at right angles thereto parallel with each other in the same plane and toward the fingers d, to which they are re-

spectively adjacent, as shown in Fig. 2, the shaft and arms being bedded in suitable recesses formed in the peripheral surface of the cylinder 6. A rock-arm *i* is formed or secured 5 on the end of the shaft 14 farthest from the spur-gear 8, this arm projecting at a right angle from the shaft and at a proper angle to the plane occupied by the tripping-arms *h*. The rock-arm *i* is loosely positioned in a recess *j*, having communication at the inner end with the circular channel *j'*, formed in one end wall of the cylinder 6, this provision permitting said end of the cylinder to work closely to one side wall 5 of the box-body and provide proper space at this end of the cylinder 10 to insure that the heads of the matches A will not have frictional contact therewith when the cylinder is moved.

A stud *m* projects from the inner surface of 20 the side wall 5 adjacent to the rock-arm *i* and in the path of said arm by entering the circular channel *j'*, so that upon turning the cylinder 6 on the direction of the arrow *x* the contact of the rock-arm with the stud will rock the shaft 14 and correspondingly rock the tripping-arms *h* outward or from the periphery of the cylinder, as shown in Fig. 4.

On the fixed top section 5^b of the box-body a stop 15 is secured and projects over the cylinder 6 at a point between the sides 5, which 30 will locate it between the tripping-arms *h* when the cylinder is turned to dispose the rock-shaft 14 below the stop-arm. Preferably the stop 15 is in the form of a curved arm 35 and at its free end may have formed thereon an upturned abutment-flange *n*, and the curvature of the stop 15 is such that the free end is located near the peripheral surface of the cylinder 6.

40 As shown, the tray-board 7 and ledge 7^a thereon afford an inclined support for matches A, that may be deposited on the tray-board, and will normally assume a transverse position, resting against the cylinder 6 and the ledge 7^a, the heads of the matches being removed a proper distance from the side wall 5 of the box, toward which they project. Assuming that a number of matches have been placed in position on the tray-board 7 and the 45 spring-motor is wound up so as to adapt it to transmit rotary motion through the intermediate gear-train to the cylinder 6, it will be seen that the rotary movement of the cylinder 6 will, if the fingers *d* are above the matches A, cause said fingers to pass upward, through the notches *e* in the edge of the tray-board and in the ledge 7^a, into engagement with the matches that lie close to the latter. The continued rotatable movement of the cylinder 6 in the direction of the arrow *x* will 50 cause the fingers *d* to lift one or more matches A as they pile upon the fingers, as shown in Fig. 3. The rock-shaft 14 is so relatively positioned with regard to the fingers *d* that the depressed tripping-arms *h* will pass be-

neath the uppermost matches that are supported on the fingers *d* an instant before the rock-arm *i* comes into contact with the abutment-stud *m*. The rock-arm *i* is rocked downward by its impingement upon the stud *m*, 70 and the tripping-arms *h* move outward so as to dislodge the matches A that are piled upon the lower one, which is directly engaged by the fingers *d*. After the stud *m* is passed by the rock-arm *i* the weight of the tripping-arms *h* will cause them to return to a normal position in the recesses formed to receive them in the surface of the cylinder 6. The single match A is now moved upward by the fingers *d* until it is brought into contact with the stop-arm 15, which will hold the match and obviously arrest the rotatable movement of the cylinder 6. An opening or cavity *o* of proper form is made in the periphery of the cylinder 6 at a point that will permit the match 80 that is held as shown in Fig. 1 to be gripped between the thumb and fingers of a person's hand, and thus facilitate the removal of the match as occasion may require. Upon the withdrawal of the match from between the fingers *d* and stop-arm 15 the motor will resume motion and turn the cylinder 6 sufficiently in the direction of the arrow *x* to pass the fingers below the matches held on the inclined tray-board 7 and again elevate one or 90 more matches, the surplus of which will be dislodged from the fingers, as before explained, and it will be apparent that the operation of the mechanical details of the matchbox may be indefinitely repeated while a supply 100 of matches is placed upon the tray-board and the motor is wound up so as to adapt it to transmit motion to the cylinder.

A motive power other than a spring may be employed for turning the cylinder of the device, and I do not restrict the construction to the spring as a motive force, as a small electric motor may obviously be employed, or the gravity of weight may be substituted for a spring within the scope of the invention. 105

Having thus described my invention, I claim as new and desire to secure by Letters Patent—

1. A mechanically - operated match - box, comprising a box-body, a cylinder held to rotate therein, a tray-board held in the box-body and inclined toward the cylinder, fingers on the cylinder, adapted to pick up a match from the tray-board, a stop on the top of the box-body, that arrests the rotary movement of the cylinder by contact with a match carried by the fingers, and means for rotating the cylinder. 115

2. A mechanically - operated match - box, comprising a box-body, a cylinder held to rotate therein, an inclined tray-board held between the sides of the box-body and extended near the lower side of the cylinder, fingers projected tangentially from the periphery of the cylinder and adapted to pick up one or more matches from the tray-board, a rock- 125

shaft carried by the cylinder and having tripping-arms thereon and a rock-arm at one end, an abutment-stud on the box-body, whereon the rock-arm may impinge when the cylinder 5 is rotated and cause the tripping-arms to dislodge surplus matches from the fingers, a stop on the top of the box-body that arrests the rotary movement of the cylinder by contact with a match carried by the fingers, and means for 10 rotating the cylinder.

3. A mechanically - operated match - box, comprising a box-body having parallel side walls and an apertured top wall, a cylinder pivoted between the sides of the box-body, an 15 inclined tray-board held between the sides of the box and extended close to the lower portion of the cylinder, fingers projected tangentially from the periphery of the cylinder and adapted to pick up one or more matches from 20 the tray-board, a rock-shaft having tripping-arms thereon, held to rock in recesses in the periphery of the cylinder, a rock-arm on one end of the rock-shaft, an abutment on one side of the box-body, whereon the rock-arm will 25 impinge when the cylinder is rotated and cause

the tripping-arms to dislodge surplus matches from the fingers, a stop-arm on the top wall of the box-body, that projects above the cylinder and arrests the rotatable movement of the cylinder when a match carried by the fingers has contact therewith, and a motor connected by gearing with a pivot of the cylinder and adapted to transmit motion thereto when a lifted match is removed from between the fingers and stop-arm. 30

4. In a device of the character described, the mechanically-rotated cylinder pivoted in the match-box body, fingers on the cylinder, the tray-board which feed matches to the fingers, the means for removing surplus matches from 35 the fingers, and the motor having geared connection with the cylinder for its rotation. 40

In testimony whereof I have signed my name to this specification in the presence of two subscribing witnesses.

EDWARD C. CARRIS.
